(57) **CLAIM**

The ornamental design for a display screen or portion thereof with graphical user interface, as shown and described.

DESCRIPTION

The FIGURE is a front view of a display screen or portion thereof with graphical user interface, showing the new design.

The outermost broken line in the FIGURE illustrates a portion of a display screen that forms no part of the claimed design. Similarly, the remaining broken lines represent features of the graphical user interface that form no part of the claimed design.
